DESIGN FOR SILK CREPE DRESS GOODS OR SIMILAR ARTICLE

Henry Bosehans, Fair Lawn, N. J., assignor to Print Textile Corporation, a corporation of
New York

Application January 13, 1936, Serial No. 60,552

Term of patent 3½ years

To all whom it may concern:

Be it known that I, Henry Bosehans, a citizen of the United States and a resident of Fair Lawn, in the county of Bergen and State of New Jersey, have invented a certain new, original, and ornamental Design for Silk Crepe Dress Goods or Similar Article, of which the following is a specification, reference being had to the accompanying drawing, forming part thereof, wherein:

The drawing is a plan view of a piece of silk crepe material showing my new design, the lining thereon representing contrasting colors.

I claim:

The ornamental design for silk crepe dress goods or similar article, as shown and described.

HENRY BOSEHANS.
